ICE DETECTOR MEANS

William B. Pond, Pomona, Calif., assignor to
Bendix Aviation Corporation, Teterboro, N. J.,
a corporation of Delaware

Original application August 11, 1943, Serial No.
498,247. Divided and this application January
10, 1949, Serial No. 70,067

3 Claims. (Cl. 244—134)

1

The present application is a division of co-pending application Serial No. 498,247, filed August 11, 1943 and now U. S. Patent No. 2,476,217, granted July 12, 1949 and assigned to Bendix Aviation Corporation, and relates to control devices and more particularly to means responsive to icing conditions prevailing on an exposed aircraft surface for operating inflatable ice eliminating units for aircraft or suitable indicator means.

It has been observed that such units or boots give better ice removal if approximately an eighth of an inch of ice is allowed to accumulate before the boots are inflated. This is because the ice must build to a definite thickness in order to develop enough tensile strength to overcome adhesion. If the inflatable ice eliminating boots are operated with insufficient ice accumulated on them, the stretch of the rubber cracks the thin layer of ice, breaking it into many very small pieces, some of which are dislodged, but most of which remain. Further accumulation of ice builds on the little particles which remain and thus develops a flexible ice which is really composed of a number of separate little islands. Once such a condition has been established, additional cycles of inflation and deflation are relatively ineffective because further ice formation tends to accumulate only on the remaining particles and the stretch of the rubber naturally localizes in the areas between the islands without disturbing them. However, if the ice be permitted to accumulate to a greater thickness, it becomes increasingly more difficult to apply sufficient pressure through the boots to effect the cracking of the ice to facilitate its removal.

It is therefore of extreme importance that the operator of the plane be so advised or that the inflatable ice eliminating boots be operated when the ice has accumulated to the optimum thickness for its removal.

An object of my invention therefore is to provide control means responsive upon such predetermined optimum icing conditions prevailing on an aircraft surface to operate suitable ice eliminating means for removing the accumulated ice from such surface, whereby said control means is simultaneously conditioned for re-operation upon a recurrence of such optimum predetermined condition.

Another object of my invention is to provide electronic control means directly responsive to the thickness of an ice accumulation for performing a control function.

Another object of my invention is to provide

2

means mounted directly upon a boot responsive to an ice accumulation thereon for initiating the operation of the boot.

Another object of my invention is to provide a novel resistance leak element mounted upon an inflatable ice eliminating boot and responsive to the formation of a predetermined thickness of ice upon the boot so as to control an electronic circuit for initiating the operation of the boot, whereupon the ice accumulation will be removed and the resistance leak element reconditioned for response to a recurrent formation of a predetermined thickness of ice upon the boot.

Another object of my invention is to provide control means responsive to ice thickness and means for removing the ice from the control means operated by the said ice thickness responsive means.

A further object of my invention is to provide a compact control device responsive to ice thickness of great efficiency in comparison to its size and of such simplicity in construction as to adapt it for manufacture and installation at low cost.

Other objects and advantages of this invention are set forth in the following description, taken with the accompanying drawings; and the novel features thereof are pointed out in the appended claims. The disclosure, however, is illustrative only and we may make changes in detail, especially in matters of shape, size and arrangement of parts within the principle of the invention to the full extent indicated by the broad and general meanings of the terms in which the appended claims are expressed.

In the accompanying drawings which form a part of this specification like characters of reference indicate like parts in the several views therein.

Figure 1 is a cross sectional view of a portion 40 of the forward edge of a wing of a plane illustrating the application of one form of my control device.

Figure 2 is an enlarged section view of Figure 1 taken along the lines 7—7 and looking in the 45 direction of the arrows.

Figure 3 is a diagrammatic view illustrating a form of control circuit which may be utilized with my control device of Figure 1.

In the form of my invention illustrated in Figures 1 through 3, there is indicated by numeral 50 110 an airplane wing provided with an inflatable ice eliminating boot 111 formed of resilient rubber like material and positioned along the leading edge of the wing 110.

The boot 111 may be of the type shown for

example in the copending application of Donald M. Lawrence, David Gregg and Myron L. Taylor, Serial No. 498,248, filed August 11, 1943 now Patent No. 2,515,519 issued July 18, 1950 and owned by the assignee of the present application and has provided inflatable tubes 112 and 113.

The tubes 112 and 113 are expanded and contracted in a recurring cycle of operation at intervals which may be determined by a timing arrangement such as shown in the copending application of Myron L. Taylor, William B. Pond and Herbert A. Eayrs, Serial No. 498,250, filed August 11, 1943 and now U. S. Patent No. 2,444,208, granted June 29, 1948 and assigned to Bendix Aviation Corporation.

In the form of the invention illustrated in Figures 1-3 there is shown a control device 99 which comprises a sleeve 100 screw threaded at the opposite ends and formed of suitable electrically conducting material. The sleeve 100 has provided a projecting annular flange 101 positioned intermediate the opposite ends thereof. A second flange 102 likewise formed of electrically conducting material is screw threadedly engaged at one end of the sleeve 100 in spaced relation to the flange 101. Concentrically mounted within the sleeve 100 is an insulation member 103 formed of a suitable moisture repellent material such as porcelain or other ceramic material suitably treated in a manner well known in the art so as to retard wetting of the surface of the insulation member 103 and thereby maintain high surface resistivity.

The insulation member 103 may be fastened within the sleeve 100 by means of any suitable material and has provided a portion 104 which projects from the outer end of the sleeve 100 through the flange 102. The outer end of the insulation member 103 has mounted thereon a pointed cap-like member 105 which is fastened thereto in any suitable manner. The member 105 is formed of suitable electrically conducting material and is spaced apart from the flange 102 and the sleeve 100 by the insulation member 103. A longitudinally extending channel 106 is concentrically formed in the insulation member 103 and extends from one end thereof to the opposite end.

An electrical conductor 107 is fastened at one end by silver solder or other suitable means to the cap-like member 105. The conductor 107 extends from the cap 105 longitudinally through the channel 106. A second conductor 108 is connected to the sleeve 100 by a nut 109 adapted to be screw threadedly engaged on the sleeve 100.

As shown in Figure 1 the control device is arranged to be secured at one end in a suitable aperture formed in the leading edge of an aircraft wing 110 by the fastening nut 109. The flange portion 101 is adapted to engage the outer surface of the wing 110 while the nut 109 engages the opposite inner surface thereof so as to fasten securely the control device thereto.

The sleeve 100 projects through a suitable aperture formed in the inflatable ice eliminating boot 111 so that the flange 102 engages the outer surface of the boot 111 and is fastened in place by screw threadedly engaging the sleeve 100. Thus the boot 111 is positioned between the flanges 101 and 102 carried by the sleeve 100. The sleeve 100 as shown in Figure 1, further extends between the inflatable tubes 112 and 113 previously described.

As shown in Figure 3, the flange 102 and cap 105 spaced apart by the insulator 103 are con-

nected to a suitable control circuit through the electric conductors 107 and 108.

The said control circuit as illustrated in Figure 3, has provided an electronic valve 114 having provided a cathode 115, anode or plate 116, a shield grid 117, a control grid 118, and a heater or filament 119.

The shield grid 117 is connected by a conductor 120 to the positive terminal of a suitable source of electrical energy 121. The negative terminal of the source of electrical energy 121 is connected by a conductor 122 to the positive terminal of the source of electrical energy 123. The negative terminal of the source of electrical energy 123 is connected by a conductor 124 to one terminal of a grid resistance 125. The opposite terminal of the grid resistance 125 is connected by a conductor 126 to the control grid 118. The cathode 115 is connected by a conductor 127 to the conductor 122 leading from the negative terminal of the source of electrical energy 121 to the positive terminal of the source of electrical energy 123.

The filament 119 is connected at one terminal 23 to the conductor 127 leading to the negative terminal of the source of electrical energy 121 while the opposite terminal of the filament 119 is connected to one terminal of a filament resistance 128. The opposite terminal of the resistance 128 30 is connected to the conductor 120 leading to the positive terminal of the source of electrical energy 121.

The anode or plate 116 is connected by a conductor 129 to one terminal of an electromagnetic 35 coil 130. The opposite terminal of the coil 130 is connected by a conductor 131 to the conductor 120, leading to the positive terminal of the source of electrical energy 121.

The electromagnetic coil 130 is so arranged that 40 upon sufficient energization thereof, spring tensioned switch arms 132 and 132A will be actuated so as to close switch contacts 133 and 133A, respectively. The switch arms 132 and 132A are normally biased by spring tension so as to open 45 the contact 133 and 133A, respectively, upon insufficient energization of the electromagnet 130.

An electrical conductor 134 connects the switch arm 132 preferably into a timer circuit of the type shown in the copending application of Myron L. Taylor, William B. Pond, and Herbert A. Eayrs, Serial No. 498,250, filed August 11, 1943 and now U. S. Patent No. 2,444,208, granted June 29, 1948 and assigned to Bendix Aviation Corporation, and indicated generally in Figure 3 by the numeral 135 while the switch contact 133 is also connected into the circuit by a conductor 136. As described in the latter application, the switch arm 132 may be arranged for closing a circuit for initiating a cycle of operation.

Similarly the switch arm 132A is arranged to 60 control a circuit for operating a suitable indicator 135A such as a light, alarm or whistle.

It will be further noted that the cap 105 of the control device 99 is connected by the conductor 65 107 to the conductor 126 leading through the grid resistance 125 to the negative terminal of the source of electrical energy 123 while the flange 102 is electrically connected by the conductor 108 to the conductor 127 leading to the positive terminal of the aforesaid source of electrical energy 123.

As shown in Figure 2, the cap 105 and the flange 102 are spaced apart by the insulation member 103. However, upon ice being accumulated on 75 the boot of sufficient thickness as to contact both

the flange 102 and the cap 105 an electrical leakage path will be closed between the elements 102 and 105 through the ice constituting a resistance leak as shown in Figure 1. The conductivity of ice is set forth in a publication by N. Ernest Dorsey entitled: "Properties of Ordinary Water Substances," on pages 505-510 of that publication.

It will be readily seen from Figure 3 that the closing of an electrical path between the flange 102 and the cap 105 will constitute a grid resistance leak that will effect a decrease in the negative potential of the control grid 118 so as to cause an increase in the electronic flow within the electronic valve 114 to the plate 116 causing a corresponding increase in the flow of current in the plate circuit. The electromagnetic coil 130 is so arranged that upon such increase in the electronic flow in the plate circuit the electromagnetic 130 will be sufficiently energized so as to cause the actuation of the switch arm 132 into engaging relation with the contact 133. However, upon the electrical path between the cap 105 and the flange 102 being opened, there will be effected an increase in the negative potential of the control grid 118 so as to decrease the electronic flow within the electronic valve 114 to the plate 116. This decrease in the electronic flow will cause a corresponding decrease in the flow of current in the plate circuit so that the electromagnetic coil 130 will be insufficiently energized for holding the switch arms 132 and 132A so as to close contacts 133 and 133A whereupon the spring tensioned switch arms 132 and 132A will be biased into a contact opening relationship with the contacts 133 and 133A, respectively.

In the operation of my novel control device 99 upon an ice accumulation on the boot of a predetermined thickness sufficient to close an electrical path between the cap 105 and the flange 102 the electromagnet 130 will actuate the arms 132 and 132A, so as to close the contacts 133 and 133A, so as to energize the indicator 135A and cause the initiation of a cycle of operation such as explained in the U. S. Patent No. 2,444,208, whereupon the tube 113 will be inflated causing the expansion of the boot 111 at the side of the sleeve 100 adjacent the tube 113. After a time interval determined by the timer 135, the boot 111 will be deflated as explained in the aforesaid patent. Then the tube 112 will be inflated and in turn deflated expanding and contracting the boot 111, at that side of the control device 99 adjacent the boot 112.

Such inflation and deflation of the boot 111 as will be readily apparent, will cause the cracking of the ice formed thereon and adjacent the control device 99 which ice will in turn be carried away by the airflow.

The remaining boots of the plane will be inflated and deflated as explained in the U. S. Patent No. 2,444,208 until the cycle of operation is completed, whereupon operation of the inflatable ice eliminating system will cease until initiated again by the formation of an ice accumulation of sufficient thickness to close an electrical path from the cap 105 to the flange 102 causing the closing of the switch contact 133 whereupon the cycle of operation of the system will be repeated.

While in the illustrations herein I have shown my control device as controlling a timer of a type disclosed in the U. S. Patent No. 2,444,208, it will be readily apparent that if desired, the same may control any suitable type of electronic control or may control an indicator and the inflatable

ice eliminating system may be controlled manually by the pilot.

Thus, although only one embodiment of my invention has been illustrated and described, various changes in the form and relative arrangement of the parts, which will now appear to those skilled in the art, may be made without departing from the scope of the invention. Reference is therefore to be had to the appended claims 10 for a definition of the limits of the invention.

What is claimed is:

1. The combination, including a control device mounted on the wing of an airplane for indicating an accumulation of ice having a predetermined thickness, said control device including a sleeve, a flange projecting from said sleeve, an insulation member positioned in said sleeve and having one end thereof projecting from one end of said sleeve, and a cap mounted on said insulation member and positioned in spaced relation to said flange; an electrical control circuit, said flange and said cap of said control device connected in said electrical control circuit, an expandible member mounted on a surface of the wing of said airplane for removing an accumulation of ice from said surface, said flange and said cap projecting from the exterior surface of said expandible member and directly responsive to an accumulation of a predetermined thickness 30 of ice on said member for increasing electrical leakage through said control circuit, and means controlled by said leakage circuit for initiating operation of said expandible member.

2. A device of the character described, comprising, in combination, a mechanism including an expandible boot carried by an aircraft for the removal of ice accumulations on said aircraft, means for operating said expandible boot, control means for initiating operation of said boot, means 35 operatively connecting said control means to the boot operating means, said control means projecting through said boot and from the exterior surface of said boot and responsive to an accumulation on the exterior surface of said boot of a predetermined thickness of ice to cause said operating means to effect expansion of said boot, whereby upon expansion of said boot removal of said ice is effected by said boot and said control means is reconditioned for initiating operation of said boot upon succeeding accumulation 50 of ice upon the exterior surface of said boot.

3. A device of the character described, comprising, in combination, a mechanism including an expandible member carried by an aircraft for the removal of ice accumulations on said aircraft, means for operating said expandible member, an electrical control circuit for said operating means, a first electrode affixed to said expandible member, a second electrode projecting from 55 said expandible member in spaced relation to said first electrode and insulated therefrom, an electronic valve having a plate and cathode connected in said control circuit and a control grid, a source of electrical energy, means connecting the source of electrical energy between the cathode and grid, said connecting means including a resistor element between the source and grid, said source of electrical energy normally applying a control bias to said grid to prevent said 60 control circuit from effecting operation of said expandible member, one of said electrodes connected to the cathode and the other of said electrodes connected to the grid of said electronic valve to provide an electronic leakage path from the grid to the source of electrical energy, said 65 70 75

leakage path being closed between the first and second electrodes by the accumulation of ice on the expansible member, said resistor element permitting a decrease through said leakage path in the control bias applied to said grid so that the control circuit may effect, through the electronic valve, operation of the expansible member.
